FOLDING DISPLAY CONTAINER

Filed Aug. 27, 1927

UNITED STATES PATENT OFFICE

ARNOLD J. TANNER, OF NORTH HAVEN, CONNECTICUT, ASSIGNOR TO EINSON-FREEMAN CO., INC., A CORPORATION OF NEW YORK

FOLDING DISPLAY CONTAINER

Application filed August 27, 1927. Serial No. 215,813.

The present invention relates to folding display and dispensing boxes or containers, and the chief object of the invention is to provide an efficient container at a comparatively low cost. The improved container is constructed of a single blank which may be economically produced and easily folded to erect the box ready for packing merchandise, and subsequently the box may, with few simple operations, be set up by the dealer for display and dispensing purposes.

The present invention relates more particularly to a type of folding box which in the trade is known as the "broken-back" box. A box of this kind consists of a carton having both ends closed by means of tuck-in flaps and tongues. The carton is cut transversely and obliquely across the top and two sides so as to form two receptacles when the carton is folded on itself. The back of the carton is scored so as to operate as a hinge for the receptacles which are located one behind the other. Said hinge is placed off the center so that the bottom of the back receptacle lies on a higher plane than the bottom of the front receptacle and, therefore, an easel or supporting means is required for the rear receptacle.

According to this invention the box complete, including the supporting easel, is constructed of a single blank without use of any adhesive and an embodiment of the invention will be hereinafter more fully described with reference to the accompanying drawings, wherein:—

Figure 1 is a perspective view of one form of box;

Figure 2 is a perspective view showing the back of the same box, and

Figure 3 is a plan view of the blank from which the box shown in Figures 1 and 2 is constructed.

Referring to said drawings, the container is composed of a blank which is scored and cut so as to be divided into a number of integral portions, which are designated by different reference numerals, and which portions are similarly designated in the set up positions of the container, as shown in Figures 1 and 2. The said blank has a central

portion, 1, intermediate portions 2, and end portions 3 and 4. These portions are divided by means of parallel creased or scored lines *a*. The central portion 1 has extending therefrom the end portions 5 and flaps 6 and the intermediate portions 2 have extending therefrom the tongues 7. The end portion 3 is preferably of a substantially tapering shape as illustrated having diagonally disposed top edge 8 and a locking tongue 9 projecting from the bottom of said portion. Also at the lower end of the portion 3, there is an extension 10, having a notch or shoulder 11 and which extension 10 is foldable on the scored lines *b* and *c*. These scored lines are respectively provided so that the extension 10 may be folded at right angles to the container so as to form a rigid easel or support. The end portion 4 is cut out at 12 so as to provide diagonally disposed edges and extensions 13, which latter are foldable on the line *d* for the purpose hereinafter set forth. The portion 4 has a slot 14 which is arranged to engage the tongue 9 when the portions 3 and 4 are folded to form the back of the container.

The central portion 1 is cut out along the line *e*, which line is extended diagonally across the intermediate or side portions 2. The cut out line *e* is continued by scored line *f* across the two end portions 3 and 4. The portion 3 is preferably cut out at 15 to provide an opening, and which opening registers with the cut out portion 16 in the portion 4. The line *f* of the blank constitutes the hinge on which the box is folded and being off center the rear receptacle will be on a higher plane than the front receptacle.

It will be noted that the operation of folding the blank to construct the box is comparatively simple. The first operation is to fold the blank on the line *a* and the end portion 3 is folded over the end portion 4, and in which position the tongue 9 is engaged in the slot 14. The box so formed is then of a substantially rectangular shape and is, in fact, the same as an ordinary tuck-in carton. The extensions 13 of the portion 4 are then turned inwardly, and likewise the tongues 7 and flaps 6, the latter engaging the extensions 13 and 100

thus operate in conjunction with the interlocking device 9-14 to hold the container in its assembled condition. When in this condition, the container is ready for packing and to make the package complete for shipping a sleeve or wrapper is placed around the container.

In setting up the container for displaying purposes, the wrapper is removed and the container is opened by folding the same on the line *f*, and in which position the container is divided into two separate receptacles. It will be noted both receptacles are of the same depth. The said folding line *f* or hinge is off the center, therefore, the bottom of the rear receptacle is on a higher plane than the bottom of the front receptacle. This being the case it is necessary to provide a support for the back receptacle, and this support is furnished by means of the extension 10 which is folded at right angles to the container. The shoulder 11 is engaged by the bottom of the rear receptacle so as to effectually support the same and to keep the front thereof close against the rear wall of the front receptacle and in this way the goods are well displayed in tiers. In order to give stability to the support furnished by the extension 10, the latter has a tuck-in flap 17 which is tucked into the box so as to hold said extension against the box, and to further increase the rigidity the end of the extension is folded on the line *c*.

In view of the varying conditions which arise in designing packing display boxes, obviously, to meet certain conditions, modifications may be necessary in the construction and the application of the invention hereinbefore described, and it is to be understood any modifications coming fairly within the terms of the appended claims shall be covered thereby.

I claim—

A dispensing display container of the class described arranged to be folded on itself to form two receptacles hinged together; said container being composed of a single blank divided by creased lines into a central portion, side portions and end portions; said central and side portions being cut transversely; said end portions being creased transversely and off center to provide a hinge for said receptacles; said central and side portions having extending flaps and tongues arranged to close the ends of the container and form the bottoms of said receptacles; said end portions being arranged to fold one over the other, said end portions having engaging retentive means for retaining said end portions in their folded positions; the bottom of one of said receptacles being on a higher plane than the other when the container is folded and one of said portions having an extension therefrom arranged to be folded to engage and

support the receptacle of which the bottom thereof is on a higher plane.

Signed at New Haven, county of New Haven, State of Connecticut, this 26th day of August, 1927.

ARNOLD J. TANNER.
